MACHINE FOR APPLYING REINFORCING
FABRIC TO INNER SOLES

John A. Scott, St. Louis, Mo.

Application March 29, 1935, Serial No. 13,638

5 Claims. (Cl. 12—20)

This invention relates to a machine for applying reinforcing canvas strips to inner soles, and is a continuation in part of my copending application Serial No. 669,854, filed May 8, 1933 which 5 has matured into Patent No. 1,996,352 granted April 2, 1935.

The object of the present invention is to provide a method of applying a reinforcing canvas strip to the channeled side of an inner sole in 10 such a manner that the work is expedited and accomplished in an efficient and economical manner.

Another object of the invention is to provide a method of applying a reinforcing canvas strip 15 to the channeled face of an inner sole which consists in arranging a plurality of inner soles in a position to one side of the operator, bringing a strip of canvas in a position on the opposite side of the operator, placing one of the inner soles in 20 position and spraying the channeled face thereof with a rubber cement or diluted latex, attaching the end of said strip to one end of the sprayed channeled face of said inner sole, moving said inner sole and said strip attached thereto past a 25 given point, then cutting the attached portion of the strip from the remainder thereof.

Another object of the invention is to provide a machine in which the strip of canvas which has been previously treated is conveyed adjacent to 30 a suitable cutting mechanism to one side of which is arranged a spraying nozzle whereby the channeled side of an inner sole can be sprayed with a suitable rubber cement whereupon the end of said strip is applied to the inner end of 35 said rubber-coated channeled side of said inner sole and both are then moved past said cutting means and placed under pressure to secure the strip to the adhesive-coated channeled side of the inner sole and said cutting mechanism is 40 then actuated to sever the attached portion of the strip from the remainder of said strip.

Further objects of the invention are to provide 45 a machine adapted to receive a roll of canvas strip and feed the same to a severing mechanism arranged at one end of said machine, there being means provided in said machine for engaging said strip intermediate its end and said roll for automatically providing a slack in said strip after each severing operation, said machine being provided with suitable spraying means for applying 50 suitable adhesive to the channeled side of an inner sole at a point adjacent to said severing mechanism, whereupon the end portion of said strip is applied to one end of the channeled side 55 of said inner sole and both moved past said

severing mechanism in such a manner that the strip is applied under pressure to said channeled side of the inner sole and the attached portion of the strip is severed from the remainder thereof flush with the toe portion of said inner sole. 5

Still further objects of the invention are to provide a machine of the character described having a canvas strip feeding mechanism and a spraying nozzle for spraying suitable adhesive on the channeled side of an inner sole preliminary 10 to the application of the end portion of said strip thereto and having means for trapping and conveying away the excess sprayed material.

Additional objects of the invention are to provide an improved method of and machine for applying a reinforcing canvas strip to an inner sole 15 which is highly efficient in operation and in performing its intended functions.

With these and other objects in view, my invention consists in certain novel features of construction and arrangement of parts, hereinafter more fully described and claimed and illustrated in the accompanying drawings, in which—

Figure 1 is a side elevational view of my improved machine. 25

Figure 2 is a rear end elevational view of same.

Figure 3 is a transverse vertical cross section taken on line 3—3 of Figure 1.

Figure 4 is a horizontal cross section taken on line 4—4 of Figure 1. 30

Figure 5 is a horizontal cross section taken on line 5—5 of Figure 1.

Figure 6 is a fragmental detail cross section taken on line 6—6 of Figure 2.

Figure 7 is a similar view but showing the parts in actuated positions. 35

Figure 8 is a sectional enlarged detail view showing means for holding the canvas strip against return movement.

Figure 9 is an enlarged front elevational view 40 of the machine with the lower part thereof broken away.

Figure 10 is a cross section taken on line 10—10 of Figure 9.

Figure 11 is an enlarged front elevational view, 45 partly broken away, and showing the strip severing mechanism in position.

Figure 12 is a vertical detail cross section taken on line 12—12 of Figure 11.

Figure 13 is a horizontal cross section taken on line 13—13 of Figure 11. 50

Figure 14 is an enlarged horizontal cross section taken on line 14—14 of Figure 1.

Figure 15 is a detail cross section showing the inner sole in spraying position. 55

Figure 16 is a similar view but showing the inner sole partly moved outwardly from the spraying position and with the end of the canvas strip applied to the heel end of the channel portion of said inner sole.

Figure 17 is a similar view with the inner sole withdrawn from the machine and in readiness for the cutting operation with the canvas strip held taut by the guide.

10 Figure 18 is a fragmental horizontal cross section taken on line 18—18 of Figure 15.

Figure 19 is a vertical cross section taken on line 19—19 of Figure 18.

15 Figure 20 is a vertical cross section taken on line 20—20 of Figure 19.

Figure 21 is an enlarged front elevational view of the latex delivery member.

Figure 22 is an enlarged front elevational view of the air nozzle member.

20 Figure 23 is a fragmental view of said air nozzle member with the spacer in place.

Figure 24 is a diagrammatic view showing the compressed air reservoir and connections between it and the various mechanisms operated thereby and the valves for controlling said connections.

Referring by numerals to the accompanying drawings, 10 indicates a framework comprising a base structure 11, and an upper structure 12. The lower structure consists of a pair of side frames 14 connected together at their front ends by a member 15 and at their rear ends by a transversely disposed top member 16 and an angle iron 17 arranged near the lower ends thereof.

35 The upper structure consists of a front end member 18 and a rear end member 19 connected together at their upper ends by a pair of tie rods 20 and a top member 21, while the lower ends of said members 18 and 19 are secured to the base structure 10.

40 Each side frame 14 consists of a single piece casting having a front member 15 and a rear leg 23 connected together at their upper ends by a rail 24 and near their lower ends by a rail 25. An intermediate vertically disposed member 26 extends between rails 24 and 25 substantially equidistant from the legs 22 and 23.

45 The canvas strips are supplied in rolls and two rolls are generally used as indicated at A and B. Thus two canvas strips C and D of varying widths can be used with inner soles of small and large sizes. These rolls are supported in the lower structure 11 by carriers 27 and 28 which are identical in size and construction but 50 are disposed on different levels, carrier 27 supplied with roll only A being disposed above carrier 28 carrying roller B.

55 Each carrier is open on top and has a horizontally disposed bottom 29 and a vertically disposed rear wall 30 and one side wall 31. The outer side of each carrier is open and extending horizontally across said side is a bar 32. This bar is pivotally mounted at one end to the end wall 31 and has its forward end adapted to rest 60 in a U-shaped member 33 fixed to the forward end of the carrier. This forward end is preferably inclined upwardly and forwardly, as indicated at 34, and terminates in a horizontally disposed portion 34a. Carrier 27 is supported 65 at its rear end by a rod 35 fixed to and extending horizontally between intermediate frame members 26 and at its forward end by a pair of lugs 36 formed integral with the rear wall of front end member 15; the horizontal portions 34a 70 of carrier 27 resting on said lugs.

Carrier 28 is supported at its rear end by a rod 37 fixed to and extending between rear legs 23 and at its forward end on a rod 38 fixed to and extending between the intermediate frame members 26 a suitable distance below rod 35. A 5 roller 39 is journaled in each carrier adjacent to the bottom and rear end thereof and the axis of each roller is disposed parallel with the axis of the roll of canvas arranged in said carrier. The purpose of rollers 39 is to form stops for 10 the rolls and facilitate the movement of said strips. The carriers 27 and 28 are left open on their front sides to facilitate the positioning of rolls of canvass therein. The bars 32 serve to hold the rolls in place in the respective carriers. 15

The canvas strips C and D extend rearwardly from their respective rolls A and B to a slack producing mechanism 40 mounted in the rear of base structure 11, and thence upwardly over rollers 41 and 42 journaled in the rear member 20 43 of the top member 21. This top member 21 is slidably mounted for movement transversely of the machine. It consists of a flat table or plate 21a, the rear end of which is secured to said rear end member 43 while the front end 25 is secured to the front end member 44. Member 43 is provided with a downwardly presented transversely disposed seat 43a which slidably rests upon the horizontally and transversely disposed flange of the upper end 19a of rear member 19. 30

Member 43 is formed with rearward extensions 43b in which are journaled side rollers 41 and 42 and with upward extensions 43c in which are pivotally mounted horizontally and transversely disposed retainers 45. These retainers extend 35 obliquely and forwardly and are provided at their lower edges with teeth which rest upon the canvas strip and prevent rearward movement thereof, without interfering with the forward movement.

The front end member 44 is provided with a 40 downwardly presented seat 44a which slidably rests upon the horizontally and transversely disposed flange of the upper end 18a of the front member 18. This front end member 44 is provided at each end with a forward extension 44b 45 in which are journaled rollers 46 over which the canvas strips pass downwardly. Pivotally mounted on said extensions 44b is the upper end of a vertically disposed guide or track member 47 over which the strips are passed downwardly. This 50 guide is spaced forwardly of the front member 18 and is provided at each side with a longitudinally disposed flange 47a which serves to confine the strips in proper positions. A spring 48 serves to hold the lower end of said guide yieldably in an 55 extended position, as shown in Figures 9 and 10. As stated before there are two rolls A and B of canvas strips provided. These strips are of different widths, strip D of roll B being of greater 60 width than strip C of roll A. The purpose of providing two strips of different widths is to permit the use of the narrow strip with small size inner soles and of the wide strip with large sized inner soles. The two strips are disposed side by side and are always ready for use. Either strip can 65 be placed in operating position by the shifting of carriage or top member 21 and its end members 43 and 44 on the upper ends 18a and 19a of the frame. As shown in the drawings, the carriage 21 is so located that the narrow strip C is in 70 operating position while the wide strip D is to one side of the operating line.

The lower end of this guide terminates above and to one side of a suitable severing mechanism 49 which is disposed on the outer side of member 75

15 adjacent to a table or shelf 50. The latter is mounted on member 15 and extends forwardly therefrom substantially on a horizontal plane with an elongated horizontally disposed opening 51 formed in member 15. The severing mechanism 49 is in the instant case in the form of a shears presented with their open ends toward the operating side of the machine, as shown in Figure 11.

5 The stationary or lower blade 49a of the shears is disposed slightly above the horizontal plane of said table 50 and said opening 51. The guide 47 is held yieldably by spring 48 in an extended or outward position as shown in Figures 10, 15 and 16 but is moved inwardly into the position shown 15 in Figure 17 just before the severing mechanism 49 is set in operation, as hereinafter more fully described.

Member 15 is preferably in the form of a vertically disposed narrow box having an exhaust chamber 15a. The front of this box is closed by a door 15b and the table 50 and said severing mechanism 49 are preferably mounted on said door. A packing 52 is arranged between said door 15b and the door opening in member 15 in order 25 to provide a substantially air-tight joint when the door is closed.

Table 50 is formed adjacent to its point of secured to said door 15b with a stepped portion 50a so as to provide the necessary clearance 30 for blade 49a and a guard plate 53, which latter is secured to said stepped portion 50a in spaced-apart relation with the severing mechanism 49 and extends upwardly a suitable distance above table 50. A horizontally disposed opening 53a is 35 formed in said guard plate through which the free end of the canvas strip is threaded and through which the inner sole is passed outwardly. This guard plate prevents the hand of the operator from coming in contact with the severing means 49 and protects it against injury.

40 Formed in the upper end of lower structure 11 is a box-shaped compartment 54, the bottom wall of which is formed by a horizontally disposed plate 55 secured to inwardly extending flanges 24a of side rails 24, while the latter form the side walls of said compartment 54. Member 16 forms the rear wall and member 15 the front wall of said compartment 54. A cover 56 is hinged to one of the rails 14 and forms the top wall for the intermediate portion of compartment 54. The rear portion of this compartment is closed permanently by a plate 51. A partition wall 58 extends longitudinally in compartment 54 and is co-extensive with cover 56. Thus the compartment 54 is divided into two longitudinal chambers 54a and 54b which communicate with each other at their rear ends and are separated from each other at their front ends by a wall 59 which extends between member 15 and the corresponding end of partition wall 58.

60 The forward end 54d of chamber 54a is open on top and receives the inner sole to be sprayed. The bottom wall 55a of this open end slopes downwardly and rearwardly toward the covered portion of chamber 54a and at a point of juncture with the horizontal bottom wall 55 a plate 60 of comparatively short height is secured transversely of the chamber. This plate serves to arrest the surplus spray material which may collect on said bottom. A drain opening 60a is formed in said bottom wall 55a adjacent to said plate and allows the liquid collected therein to drain into a receptacle 61 supported in said base structure 11 below said drain opening.

75 The chamber 54a is provided with a plurality

of spaced-apart baffle plates 62. These plates are removable for cleaning purposes and preferably they are attached to partition wall 58 which is also removable. The air and spent sprayed material are drawn into chamber 54a and in 5 passing therethrough the latex carried by the air is deposited on said baffle plates. The air then passes from chamber 54a to chamber 54b and passes forwardly therethrough and enters chamber 15a through an opening 54c. A cover 63 10 closes the front end of chamber 54b.

The lower end of chamber 15a is provided with an opening 64 in which operates an exhaust fan or blower 65 enclosed by a housing 66. An air discharge 67 leads from said housing and opens 15 to the atmosphere. Blower 65 is operated by an electric motor 68 mounted in the base structure 11.

Thus the air is drawn from the spraying chamber 54d through chambers 54a and 54b, thence 20 through opening 54c into exhaust chamber 15a. From this chamber it is then exhausted by the blower 65 and discharged to the atmosphere through the discharge conduit 67.

The latex particles contained in the air are 25 deposited on the baffle plates 62 and on the walls of the respective chambers 54a and 54b so that the air upon reaching the blower and the discharge conduit 67 is practically free of all latex. As the baffle plates 62 and partition wall 58 are 30 removable, they can be readily cleaned at regular intervals of the accumulated latex deposited thereon. Chambers 54a and 54b can be cleaned by moving the cover 56 into open position. This cover which forms the top or table of the base 35 structure 11 can be used to hold a number of inner soles in readiness for spraying operation, as indicated in dotted lines in Figures 1 and 3. The rear edge of this cover is provided with a longitudinally disposed upwardly projecting flange 40 56a which serves to hold the soles in position on said cover.

A block 69 is fixed to the front wall of spraying chamber 54d below the discharge opening 51 and fixed to said block and extending rearwardly 45 therefrom into said chamber 54d is a pair of rearwardly diverging arms or rods 70 which form the support for the inner sole during the spraying operation. The latex is sprayed on to the channeled side of the inner sole by means of a 50 spraying nozzle 71 which is arranged a suitable distance above the inner sole support 70. This nozzle has a connection 72 extending toward a latex container 74 and a compressed air connection 75 extending to a compressed air reservoir 55 90 (see Fig. 24). This reservoir can be arranged at any suitable point with respect to the machine. The air connection 75 passes forwardly from said reservoir and then downwardly exteriorly of the operating side of the machine and is provided 60 with a valve 77 normally closed and operable by a lever 78 into open position to allow the passage of air from the reservoir to the nozzle. This lever is pivotally mounted on the machine, as indicated at 79, and is so arranged that it can be operated 65 by the left knee of the operator when the latter stands in operating position.

The latex container 74 is arranged rearwardly of the spraying chamber 54d and is supported on the cover 63 at a horizontal plane above the 70 plane of nozzle 71. Preferably this container is sealed on top and is provided at its lower end with an extension or well 78' which is of comparatively small area and is open on top and adapted to receive the upper end of the latex sup- 75

- ply connection 72. A supply of latex is automatically maintained in said well at a predetermined level and the end of the connection 72 is disposed below said level.
- 5 The spraying nozzle 71 consists of two sections, namely, the latex section 71a and the compressed air section 71b. These sections are so arranged that they can be readily connected together or disassembled without disturbing the compressed air connections so that the latex section 71a can be easily removed for cleaning purposes.
- This section 71a consists of a tubular elbow member 80 having a reduced end 80a connected to one end of pipe connection 72 and having its 15 opposite end 80b tapered exteriorly and formed with an enlarged bore 81, thereby forming therein an annular shoulder or seat 81a.
- The compressed air section 71b consists of a block 82 having a curved lower end and provided 20 with a longitudinally disposed bore 83 closed near said lower end and open at the other to receive the compressed air pipe 76. This block is formed on one side at its lower end with a concave or semi-spherical recess 84 which communicates 25 with the inner or closed end of bore 83 through an opening 85.
- A washer or cylindrical member 86 is secured to the recessed side of block 82 by a screw 87 coaxially with said recess. The diameter of this 30 member 86 is larger than the diameter of said recess so that the latter is closed except at the lower portion which is left open by virtue of the fact that a portion of the peripheral face of said member 86 is cut away, as indicated at 86a. Immediately below this open portion of the recess the recessed face of the block is formed with a plurality of notches or grooves 88 which extend outwardly from said recess to the curved end of 35 said block and form outlets therefor.
- 40 The diameter of bore 81 of member 80 is slightly larger than the diameter of member 86 so that the latter can be conveniently inserted therein when the sections 71a and 71b are assembled together.
- 45 When thus assembled, a discharge passage is formed between the wall of bore 81 and the cut-away portion 86a through which latex is drawn from member 80. Member 86 is so positioned that the cut-away portion 86a is arranged adjacent 50 to notches 88, thereby locating the open portion of the member 80 opposite to notches 88. Thus when the air is discharged from recess 84 through said notches 88 the latex is drawn from member 80 through the opening formed by cut-away portion 86a and is mixed with the air and then 55 sprayed upon the channeled face of the inner sole held in position on supports 70.
- The screw 87 extends through opening 85 and the lower end of bore 83 and this screw is of smaller diameter than either one of these so that the 60 passage of air therethrough is not effected.
- A pipe 91 having a valve 92 connects tank 90 with a cylinder 94 in which operates a piston 95. This cylinder is located at the top of the forward 65 end of the machine above plate 21 and piston 95 bears against the upper end of guide 47. Normally, spring 48 holds said guide in extended position shown in Figures 10, 15 and 16. When compressed air is admitted to cylinder 94, piston 70 95 is moved outwardly, thereby rocking said guide 47 on its pivot 44b so that the lower end of said guide moves inwardly, as shown in Figure 17, thereby holding the strip of canvas between the inner sole and the lower end of said guide taut 75 in readiness for the cutting operation.

A pedal 96 is used to operate cutting mechanism 49. This pedal is pivotally mounted on the door 15b, as indicated at 97, and has its rear end pivotally connected to the lower end of a link 98. The upper end of this link is pivotally 5 connected to an extension 49b of the movable blade 49. A coiled spring 99 is anchored at one end to door 15b and at its other end is connected to a member 100 which is adjustably fixed to link 98. The tendency of the spring is 10 to hold the blade in open position and link 98 and the rear portion of pedal 96 in depressed position, as shown in Figure 11.

The forward end of pedal 96 is bent at right angle as indicated at 96a and extends in front 15 of the operating side of the machine and below the knee-operated lever 18. A vertically slidable member 101 is mounted on the side of the machine and has its lower end bent laterally and forwardly to extend under the portion 96a of 20 said pedal so that when the latter is operated, member 101 is caused to move downwardly. A coiled spring 102 is connected to the upper end of member 101 and yieldably holds said member 25 in normal or raised position.

The slack producing means 40 is operated by a piston 104 operating in a cylinder 105. This air cylinder is connected to tank 90 by a pipe 106. A valve 107 controls the passage of air 30 through said pipe 105.

It is desirable that the piston 95 be actuated before the piston 105 in order to obtain proper taut condition of the strip at the severing operation and before slack is produced in the strip. To this end, valves 92 and 107 are arranged in 35 spaced-apart rotation with each other to one side of member 101. A slidably horizontally disposed plunger 108 is interposed between member 101 and valve 92 and is adapted to be actuated when member 101 is depressed by the high 40 portion 101b of said member so as to open valve 92. A similarly disposed plunger 109 is arranged between valve 107 and member 101 and is adapted to be actuated by the high portion 101c of said member 101. The high portion 101c is spaced 45 from plunger 109 so that the operation of plunger 108 and valve 92 takes place a predetermined length of time before plunger 109 and valve 107 are actuated.

The pedal 96 is so arranged with respect to 50 member 101 and link 98 that the actuation of plunger 108 and of the valve 92 and the corresponding piston 95 takes place before the severing operation of the strip. Thus the guide 47 is moved inwardly and holds the strip taut before 55 the movable blade 49a is brought down while the operation of plunger 109 and valve 107 takes place after the severing operation. The valves 92 and 107 are of the "bleeder" type which permits the discharge of the air to atmosphere 60 from the respective cylinders after each operation.

The slack producing means 40 which is mounted in the rear end of the base structure 11 is designed to produce slack in the canvas strip 65 between the roll portion thereof and the canvas strip retaining member 45. Thus the canvas strip can be easily pulled through the machine when the forward end portion thereof is applied to the sole and the two moved forward together 70 before the severing operation takes place.

This slack producing means includes a pair of rollers 110 revolvably mounted in bearings 111 and a movable roller 112 which is journaled in bearings 114 formed in a movable carriage 115. 75

The bearings 111 are fixed on said rear end of structure 11 and the carriage 115 is slidably mounted in said structure 11. The stationary rollers 110 are horizontally disposed and are 5 spaced transversely from each other a sufficient distance to permit the movable roller 112 to operate therebetween in a plane at right angles to the horizontal plane of the axis of rollers 110.

The carriage 115 is fixed to the upper end 10 of a piston rod 116 and this rod extends into a cylinder 105 and is fixed at its lower end to piston 104 disposed in said cylinder.

Normally, or with the cylinder 105 disconnected from the compressed air supply, the movable 15 roller 112 occupies position below the horizontal plane of rollers 110 and the canvas strip, after the slack has been taken up, extends under and across said rollers 110. When the piston 104 is actuated by the operation of valve 107, carriage 115 and roller 112 are carried upwardly. The extent of movement of roller 112 is a suitable distance past the rollers 110. During this movement said roller 112 engages that portion 20 of the canvas strip extending between rollers 110 and moves said portion upwardly past said roller as shown in Figure 7. As the canvas strip is held against retrograde movement by member 45, the upward movement of roller 112 causes the roll of canvas to unroll to provide the necessary slack in the canvas strip. When two rolls 25 of canvas, as A and B, are used, two sets of rollers 110 are used and the carriage 115 is also provided with two rollers 112.

On the downward movement of carriage 115 30 and rollers 112, a suitable length of canvas is released to produce the slack which can be readily taken up when the forward end portion of the canvas is applied to the sole at the front end of the machine.

In the operation of the machine, a plurality 35 of soles is placed on table or shelf 56, the flange 56a forming a stop to prevent the soles from falling back of the machine. The operator stands in front of the machine adjacent to the forward end thereof. He takes one of the soles 40 E and places it on member 70 with the channel F thereof presented toward the spray nozzle 71 and with the heel portion G presented forwardly and extending outwardly through opening 51. He then presses with his knee lever 78, thereby 45 releasing compressed air so that the adhesive or latex is sprayed through said nozzle on to the channeled side of the sole. The operator now moves the sprayed inner sole forwardly until the heel end G projects through opening 53 of plate 52. He then grasps the projecting heel end G with his left hand and draws the sole forwardly through opening 51. When the heel end H of the channel F is flush with the free end 50 of the canvas strip C, he presses said end of the strip against the adhesive-coated face of the sole and grasps both the sole and said strip end and pulls them forward, as shown in Figure 16, at the same time pressing the canvas portion 55 against the channel face so as to cause it to adhere thereto.

When the toe portion of the sole E passes the upwardly presented edge of blade 49a, the operator presses the pedal 96. This actuates piston 95, causing the lower end of guide 47 to move rearwardly, thereby rendering and holding the canvas strip between the sole and the pin 47b taut. Immediately after this operation, the movable blade 49 is actuated to come against the stationary blade 49a thereby severing the strip 70 75

portion attached to the sole from the base of the strip. The operator now removes the sole with the strip attached thereto and inserts a new sole into the machine on member 70 and repeats the operation. 5

When pulling on the forward end of this strip, the slack portion is taken up and it is not necessary to exert a great deal of pull. The slack producing mechanism 40 is automatically set in operation immediately after each severing operation so as to produce slack in the strip for the next sole. 10

The machine can be used for applying canvas strips to outer soles as well as inner soles. 15

By using compressed air to apply the adhesive on to the channel face of the sole, the adhesive is forced under pressure against the leather. It is desirable to use about thirty pounds of air pressure to force the adhesive or latex in a fine spray against the sole. The adhesive used is 20 preferably a liquid latex which is a commercial product and is composed of rubber and water with a very slight proportion of ammonia or other ingredients for the purpose of preserving it and preventing coagulation before being used. 25

By using air pressure the latex is forced into the fibers of the sole and particularly the channeled part thereof. Thus a thorough impregnation of the pores of the leather by the latex is 30 provided, thereby obtaining a very efficient bond between the canvas and the leather.

It is not necessary to make any exposure of the coated sole as there is no volatile solvent used in the liquid latex. After the canvas is cut out the canvas can be immediately pressed onto the sole and creased along the channeled portion thereof. Thus there is no waste of time between the spraying operation of the sole and the finishing operation. However, the sole can be sprayed 35 and the canvas pressed thereto and creased after an interval of time or to suit the convenience of the operator, if so desired. 40

The application of the latex to the sole is important as it is well known that where rubber cement is used, two surfaces can not be united 45 in a satisfactory manner without both surfaces receiving a coating of rubber cement. By spraying the sole with latex, both surfaces are rubber coated (the canvas has been pre-treated) and when pressed together adhere much more firmly 50 than if the cement were applied to the canvas only and then the coated canvas applied to the dry surface of the sole. 55

I claim:

1. A machine of the character described comprising in combination a frame, means on said frame for supporting a roll of canvas strip, means for supporting a portion of said canvas strip in unrolled position with the end of said unrolled portion extending downwardly, a guide for receiving and guiding said downwardly presented end of said strip portion, means for supporting an inner sole in a position to one side of said guide with one end of said inner sole in close proximity to the free end of said downwardly 60 presented strip portion, and a spraying nozzle for spraying the channeled face of said inner sole with a rubber solution whereby said end portion can be applied to the sprayed channeled face of said inner sole, and means for severing the attached strip portion from the balance of the strip. 65

2. A machine of the character described comprising in combination a frame, means on said frame for supporting a plurality of inner soles to 70 75

the right side of the operator, a canvas strip guide arranged on said frame on the left side of the operator, a nozzle disposed in said frame between said guide and said inner sole supporting means, 5 and a member disposed in said frame adjacent to said nozzle for supporting each inner sole with the channeled face thereof presented toward said nozzle whereby said channeled face is sprayed from said nozzle.

10 3. A machine of the character described comprising in combination a frame, a support on said frame for a roll of fabric, a substantially vertical channel on said frame for guiding fabric from said roll in said frame, a supporting table adjacent the lower end of said channel, a nozzle for liquid cement arranged in said frame, a member in said frame for supporting an innersole in substantially horizontal position to receive cement from said nozzle, the lower end of said guide 15 and said member being arranged adjacent said table to permit an operator to apply the free end of said fabric to one end of the cemented face of said innersole and to move the innersole onto said table with said fabric covering the cemented 20 face of said sole, and severing mechanism on said table for cutting off from said roll that portion of the strip covering the cemented face of said sole.

25 4. In a machine of the character described, supporting framework, means for supporting a roll of fabric on said framework, a substantially horizontal support, means arranged above said support for spraying under pressure a liquid ce-

ment against an innersole adapted to be positioned on said support, a table on said framework laterally displaced with respect to said member, means for guiding the strip of fabric toward said table with its free end adjacent to said member and located to enable an operator to apply the free end of the fabric to one end of the cemented face of an innersole and draw the fabric and innersole in superposed relation onto said table, and means for severing from the said 10 roll the fabric superposed over the cemented face of said innersole.

5 5. A machine for applying a reinforcing canvas strip from a roll to leather soles and comprising a frame, a severing means arranged in said frame, means for supporting an unrolled portion of said canvas with its free end adjacent to the severing means, a spraying nozzle arranged in the frame adjacent to and above said severing means, a table on said frame, a member in the 15 frame for supporting a sole adjacent to and below said nozzle to be sprayed with cement from said nozzle, said member and means being arranged to enable an operator to apply the free end of the strip to one end of the sprayed face of the 20 sole, and to move the strip and sole simultaneously onto said table with the strip covering the sprayed face of said sole, and means for operating the severing mechanism to separate the strip 25 covering said sole from the roll of fabric. 30

JOHN A. SCOTT.
